Patented Apr. 30, 1968

210,883

STEREO PHONOGRAPH CARTRIDGE

Kenkichi Tsukamoto, 47 Koyama-Shimofusa-machi,
Kita-ku, Kyoto-shi, Japan

Continuation of design application Ser. No. 3,740, Sept. 6,
1966. This application Nov. 7, 1966, Ser. No. 5,123

Term of patent 14 years

(Cl. D26—14)

FIG. 1

FIG. 2

FIG. 3

FIG. 4

FIG. 5

FIG. 1 is a front elevational view of a stereo phonograph cartridge showing my new design.

FIG. 2 is a rear elevational view thereof.

FIG. 3 is a top plan view thereof.

FIG. 4 is a bottom plan view thereof.

FIG. 5 is a side elevational view, the opposite side being substantially a mirror image thereof.

This application is a continuation of my copending application, Ser. No. D. 3,740 filed Sept. 6, 1966, now abandoned.

I claim:

The ornamental design for a stereo phonograph cartridge, as shown and described.
